UNITED STATES PATENT OFFICE

166,308

CART FOR A GOLF BAG

Albert Carl Grant, Leavenworth, Kans.

Application May 2, 1950, Serial No. 9,634

Term of patent 14 years

(Cl. D14—3)

To all whom it may concern:

Be it known that I, Albert Carl Grant, a citizen of the United States residing at Leavenworth, in the county of Leavenworth and State of Kansas, have invented a new, original, and ornamental Design for a Cart for a Golf Bag, of which the following is a specification, reference being had to the accompanying drawings, forming a part hereof.

Fig. 1 is a perspective view of a cart for a golf bag, showing my new design; and

Fig. 2 is a front elevational view thereof.

I claim:

The ornamental design for a cart for a golf bag, as shown.

ALBERT CARL GRANT.
